Original application September 29, 1934, Serial
No. 746,180. Divided and this application Jan-
uary 24, 1938, Serial No. 186,601

2 Claims. (Cl. 229—52)

This invention relates to pasteboard containers and more particularly to a combined locking means and handle therefor, this application being a division of my co-pending application for Handle and locking member for pasteboard containers and the like, Serial No. 746,180, filed September 29, 1934, Patent No. 2,109,034, Feb. 22, 1938.

A major object of the invention is to provide a pasteboard container having means which provides for effectively locking the container, in addition to providing a carrying means therefor.

Another object of the invention resides in the provision of means for preventing the combined locking means and handle from becoming inadvertently disassociated from the outer section of a two section pasteboard container and yet affording easy and rapid disassembly therebetween.

With the above generally broad objects in view and with others which will become later apparent, the invention consists of a construction and combination such as illustrated in the accompanying drawing in which a preferred embodiment is shown.

In the drawing:

Fig. 1 is a perspective view of a conventional pasteboard or paper container showing the invention applied in operative position.

Fig. 2 is a view similar to Fig. 1 but showing the container in partially open position.

Fig. 3 is a sectional view through the upper wall of the container in the plane of the handle.

Fig. 4 is a transverse sectional view in the plane indicated by the line 4—4 of Fig. 3.

Fig. 5 is a view similar to Fig. 3 showing the manner of disassociating the container locking member from the outer section thereof when it is desired to open said container.

Referring to the drawing in greater detail, the container is shown as comprising an inner section 10 and an outer section 11 telescopically engaged over said inner member. These two sections are preferably made inseparable along the line 12.

The invention is designed to be used as an element to provide a carrying and locking means for pasteboard containers where either two flaps fold down upon each other in the closing operation, or where the two sections close one into the other.

The top wall or flap 13 of the inner section is preferably provided with a pair of spaced slits 14 symmetrically arranged at the center of said wall and disposed transversely to the length thereof.

The top wall or flap 15 of the outer section is preferably provided with a slot or opening 16 of

a width equal to the length of the slits 14 and substantially equal in length to the spacing of said slits. In forming the opening 16, projections or tabs 17 are left on the longitudinal edges thereof, these tabs being arranged in pairs adjacent the ends of the slot, substantially as illustrated.

The combined handle and locking member 18 is preferably formed as an elongated member of a width adapted to fit in the slits 14 and the opening 16. The central portion 19 of said member 18 is adapted to serve as a carrying handle for the container and the ends 20 thereof are formed arrow-shaped, being preferably scored as at 21 to provide fold lines upon which the wing portions 22 may be folded.

When the combined handle and locking member is to be applied to the container, the wing portions 22 are doubled over on the ends 20, passed through the opening 16, and then threaded through the respective slits 14. These wing portions will then spring outwardly as shown in Fig. 4 to provide shoulders having engagement with the under surface of the wall 13 of the inner container section 10. Now, when the handle portion 19 is grasped, the weight of the container and its contents is effectively supported by said handle and the container sections 10 and 11 are maintained locked and in closed relation. When the handle is released, the projections or tabs 17 will prevent the handle from inadvertently falling through the opening 16, being prevented from doing this by engagement of the under surface thereof with said tabs.

When it is desired to open the container, the top surface of the handle is pressed downward towards the container and the handle is forced past said tabs which spring out of their normal plane to permit removal of said handle from the opening 16 and thus disassociation of the handle from the outer container section 11. The sections may then be opened in the hinge line 12. This is illustrated in Fig. 5.

In the above manner, the container may be readily and rapidly opened and closed as many times as necessary without unduly straining or forcing portions of the container whereby it may become torn or frayed. It will be noted that the handle member 18 remains associated with the container at all times so it may not be mislaid, although it is also possible to detach said member, if desired, by merely doubling over the wing portions 22 and extracting the arrow-shaped ends 20 from their slits 14.

The combined handle and locking member may be constructed in various ways to afford a com-

fortable grip as disclosed in the mentioned co-pending application. Other features of the invention also may be constructed in various ways and for this reason, the prior art rather than the instant disclosure should form the basis of interpretation of the spirit and scope of the invention as claimed.

What I claim as new and desire to secure by Letters Patent, is:

- 10 1. A device for the purpose indicated comprising, in combination with a container having overlapping flaps or walls of which one is provided with transverse slots, and a handle having terminal arrow heads insertable through said slots, the cooperating flap or wall being formed with one slot of a length equal to the spacing of the slots in the first wall or flap and of a width equal to the length of said slots, so that the handle, when attached, may have all of that portion extending from the connected flap or wall passed through the slot in the other flap or wall, the last said slot
- 15
- 20

being formed adjacent its ends with projections arranged in pairs of oppositely disposed projections adapted to be flexed from their normal plane when the handle is passed through said slot.

2. A device for the purpose indicated comprising, in combination with a container having overlapping flaps or walls of which one is provided with transverse slots, and a handle having terminal arrow heads insertable through said slots, the cooperating flap or wall being formed with one slot of a length equal to the spacing of the slots in the first wall or flap end of a width equal to the length of said slots, so that the handle, when attached, may have all of that portion extending from the connected flap or wall passed through the slot in the other flap or wall, the last said slot being formed adjacent its ends with a projection on each side of the slot, said projections adapted to be flexed from their normal plane when the handle is passed through said slot.
